UNITED STATES PATENT OFFICE.

MERLE WOODWARD EASTMAN, OF CAMBRIDGE, MASSACHUSETTS.

MOTOR FOR DAMPER-REGULATORS.

1,314,254.

Specification of Letters Patent. Patented Aug. 26, 1919.

Application filed October 1, 1917. Serial No. 194,232.

To all whom it may concern:

Be it known that I, MERLE WOODWARD EASTMAN, a citizen of the United States, residing at Cambridge, in the county of Middlesex and State of Massachusetts, have invented certain new and useful Improvements in Motors for Damper-Regulators, of which the following is a specification.

My invention relates to motors for damper regulators for automatically operating the flue dampers to control the boiler pressure.

The object of my invention is to provide a damper regulator for steam boilers which will control the damper by the boiler pressure in such a manner that the damper will be moved by successive stages with a well defined period of rest between the various stages, and thereby maintain a more nearly uniform furnace temperature. To accomplish these results, I have produced a machine having a weighted motor, the piston of which is operated on its upward stroke, by the accumulation of water pressure, the motor having multiple valves operated by the boiler pressure for venting the cylinder at various stages, and thereby retarding the movement of the piston.

Sheet (1) Figure (1) shows a vertical section of the water motor and diaphragm chamber. Fig. (2) shows an exterior view of the water motor. Sheet (2) Fig. (3) shows a sectional view of one of the exhaust valves. Fig. (4) shows a cross section through all of the exhaust valves. Like numerals refer to like parts in the several figures.

Referring to Sheet (1) Fig. (1), (1) is the diaphragm chamber, (2) is a tapped hole for pipe connections to the boiler pressure, (3) is the pressure cap which conveys the force of the boiler pressure to scale beam (4), (5) is weights for counteracting the boiler pressure, (6) is a connecting rod which operates bell crank (7) for opening and closing the exhaust valves (8), (9) is a connection to water or other fluid under pressure. This connection is provided with a small needle valve, not shown, for limiting the flow of water, to an amount less than can be dissipated by any one of exhaust valves (8), (19), (20) or (21). (10) is a piston which operates in cylinder (11). (12) is counter-weights for operating the motor on the downward stroke. (13) is a chain or cord connection running over

sheaves or pulleys (14) and (15), to damper arm (16). (17) is a damper weight for closing damper (18). (23) and (24) are pipe connections for conveying the waste water from the exhaust chamber to the sewer, hot well, or other draining apparatus; the exhaust pipe being connected at the end most convenient, the opposite end of chamber being plugged.

Referring to Sheet (2) Fig. (4), (22) is springs for normally holding the exhaust valves closed.

The operation of the machine is as follows: Normally bell crank (7) is pressed against the ends of valve stem (8), (19), (20) and (21), compressing spring (22) and holding the exhaust valves open. The pressure being admitted at (9) through needle valve, not shown, is dissipated by being exhausted through exhaust valve (19) to the atmosphere. Whenever the boiler pressure exceeds weights (5), scale beam (4) will be raised oscillating bell crank (7), thereby allowing exhaust valve (19) to be closed by spring (22). This operation permits the accumulation of pressure under piston (10), which travels upward until the pressure is again dissipated through connection (25) Fig. (2) and exhaust valve (20). As the boiler pressure further increases valve (20) will be released from engagement with bell crank (7) allowing spring to close valve (20), and the piston will travel to a point in the motor cylinder (26), where a similar period of rest will take place, and so on as the boiler pressure increases and each successive exhaust valve is closed, until the piston (10) has made a complete stroke of cylinder (11) and closed damper (18). Connection (28) is an overflow from the top of motor cylinder to prevent the accumulation of water above piston (10). As the boiler pressure decreases the bell crank will first open exhaust valve (8), when the motor will travel on a downward stroke by the force of counter-weights (12), until it has reached a point opposite connection (27), and as the boiler pressure continues to decrease the valves will be opened in the following order. First (8), second (21), third (20), fourth (19), at which time the motor piston has returned to its starting point and the damper is entirely open. This independent action of the exhaust valves being controlled by the varying lengths of the exhaust valve stems, 110

which is successively engaged and disengaged by the bell crank.

In practice the machine seldom, if ever, makes a complete stroke of the motor, but 5 will be held at a point in its travel, which will give the necessary draft to burn the fuel under the boiler, and maintain the desired steam pressure.

As each exhaust valve spring is released 10 or compressed, a change in force takes place which is equivalent to adding or taking weights from scale beam (4), which required a further increase or decrease of pressure as the case may be, before the piston can travel 15 to the next succeeding stage. This results in a well defined period of rest at each stage of the travel of the motor.

I am well aware of the fact that damper 20 regulators for controlling boiler pressure have been used having cut-off attachment designed to hold the piston at a partial stroke, but such arrangement usually consists in compensating the movement of a single actuating valve having admission 25 and exhaust ports, and as such valves are liable to stick, the cut-off attachment is made ineffective resulting in a complete stroke of the piston. Even when the cut-off attachment is most effective, the tendency of such machines, due to the necessary friction of a closely fitted piston valve, is to travel past the point where it should stop, resulting in too great a variation in the furnace temperature, for economy.

35 My invention provides for a positive graduated movement of the piston, the number of stages of its travel being only limited to the number of exhaust valves employed.

40 The period of rest between the various stages of the travel of the piston may be made more or less to suit the conditions by adjusting the tension of the spring which holds the exhaust valve closed.

45 While the specifications describe my invention in connection with the operation of dampers for controlling the boiler pressure, I do not wish to limit the scope of the invention to this particular field, as it may 50 be successfully applied to controlling balanced lever valves, for supplying steam to blower engines or turbine blowers, or exhaust fans, as used in connection with forced or induced draft; or it may be applied to 55 the control of balanced lever valves for reducing steam pressure from a high initial to a lower reduced pressure. I therefore wish to claim my invention broadly for any use for which it may be applicable.

60 Having fully described my invention, what

I claim as new and desire to protect by Letters Patent of the United States is:

1. The combination of a motor cylinder and piston, said piston being operated by accumulative pressure and having multiple 65 exhaust valves for venting the cylinder at various points and means for actuating said exhaust valves, to cause the piston to travel in successive stages with a well defined period of rest between each stage. 70

2. The combination of a motor cylinder and piston, said piston being operated by accumulative pressure, and having multiple exhaust valves designed to be opened independent of one another, for venting the 75 cylinder at various points, and means for closing said exhaust valves, to cause the piston to travel in successive stages with a well defined period of rest between each stage. 80

3. The combination of a motor cylinder and piston, said piston being operated by accumulative pressure, and having multiple exhaust valves actuated independently of one another, means for so actuating said 85 valves, comprising a weighted device for venting the cylinder at various points to cause the piston to travel in successive stages with a well defined period of rest between each stage. 90

4. The combination of a motor cylinder and piston, said piston being operated by accumulative pressure, and having multiple exhaust valves arranged to be opened independently of one another, means for so 95 actuating said valves, comprising a weighted device for venting the cylinder at various points, and springs for closing said valve, to cause the piston to travel in successive stages with a well defined period of rest between each stage. 100

5. The combination of a motor cylinder and piston, said piston being operated by accumulative pressure, and having multiple exhaust valves held to their seats by 105 springs, and with stems of varying lengths arranged to be opened and closed independently of one another, means for so actuating said valves, comprising a weighted device for venting the cylinder at various points to 110 cause the piston to travel in successive stages, with a well defined period of rest between each stage.

In testimony whereof I have affixed my signature in presence of two witnesses.

MERLE WOODWARD EASTMAN.
